AIRCRAFT

William Coelho Thomas, 11083 Cloverlawn,
Detroit, Mich.

Filed Jan. 23, 1963, Ser. No. 73,439

Term of patent 14 years

(Cl. D71—1)

FIG. 1

FIG. 2

FIG. 3

FIG. 4

FIG. 5

FIG. 6

FIG. 7

FIGURE 1 is a perspective view of an aircraft showing my new design;

FIGURE 2 is a sectional view taken on line 2—2 of FIGURE 1;

FIGURE 3 is a side elevational view thereof;

FIGURE 4 is a transverse sectional view taken behind the cockpit;

FIGURE 5 is a rear elevational view thereof;

FIGURE 6 is a bottom plan view thereof; and

FIGURE 7 is a front elevational view thereof.

This application is a continuation-in-part of application Serial No. D-63,638 filed January 23, 1961, and now abandoned.

I claim:

The ornamental design for an aircraft, substantially as shown and described.
